UNITED STATES PATENT OFFICE.

GEORGE C. MAXWELL, OF ALLENPORT, PENNSYLVANIA.

FIRE-GRATE.

SPECIFICATION forming part of Letters Patent No. 268,256, dated November 28, 1882.

Application filed September 15, 1882. (No model.)

To all whom it may concern:

Be it known that I, GEORGE C. MAXWELL, a citizen of the United States, residing at Allenport, in the county of Washington and State of Pennsylvania, have invented certain new and useful Improvements in Fire-Grates; and I do hereby declare that the following is a full, clear, and exact description of the same, reference being had to the annexed drawings, making a part of this specification, and to the letters and figures of reference marked thereon.

Figure 1 of the drawings is a perspective view of a fire-place with my invention attached; Fig. 2, a top plan view, and Fig. 3 a side elevation from the rear.

The present invention has relation to certain new and useful improvements in that class of fire-place grates provided with hinged or sliding guards or fenders; and the object thereof is to improve the construction of this class of attachments to the grate, whereby the heated coals may be kept from falling out and setting fire to the premises, and adapting such guards or fenders for connection to any fire-place, and so that they will perfectly operate when being opened or closed. These objects I attain by the construction substantially as shown in the accompanying drawings, and hereinafter described.

In the drawings, A represents an ordinary fire-place grate, having the usual top bar, a, said grate being set in the usual fire-place front, B. Upon the back of this fire-place front, at each side, are suitable brackets, C, having guide-flanges b, in which slide the guards or fenders D, said guards or fenders also sliding on supports e of plates E, projecting from the back of the said fire-place front. These guards or fenders D are arranged on the same vertical plane with and forming an extension of the grate when drawn out for use, and are pro-

vided with feet d, which fit over and upon the top bar, a, of the grate A to admit of their being pushed to or from the center thereof, and with stops e to prevent them from being drawn too far out, said stops coming against the brackets C when the guards or fenders have reached the center of the grate. The feet d upon the guards or fenders D also act as stops to prevent them from being pushed too far back, said feet coming against the sides of the fire-place front B. The guards or fenders D are also provided with lips f, so that they may be readily drawn out with a poker or other fire-place implement engaging therewith. The guards or fenders may be readily attached to any fire-place grate, whether straight or curved, and by cutting a recess in the jamb of the fire-place can be slid back out of sight when not in use, and as readily brought forward when desired. Either of the guards or fenders may be used independently of the other, as they are designed to come only to the center of the grate when drawn out.

Having now fully described my invention, what I claim as new, and desire to secure by Letters Patent, is—

The combination, with an open grate and fire place having upon its interior side suitable brackets, C, provided with guide-flanges b, and the plates E, of the sliding open guards or fenders D, having feet d, adapted to rest over and upon the upper or top bar of the grate, substantially as and for the purpose set forth.

In testimony that I claim the above I have hereunto subscribed my name in the presence of two witnesses.

GEORGE C. MAXWELL.
